Primary Examiner — Thomas Johannes*Assistant Examiner* — Shawn T Gingrich(74) *Attorney, Agent, or Firm* — Birch, Stewart, Kolasch & Birch, LLP**(57) CLAIM**

I claim the ornamental design for a terminal for motor-protection relay, as shown and described.

DESCRIPTION

FIG. 1 is a perspective view of a terminal for motor-protection relay showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.
